(57) **CLAIM**

The ornamental design for vial windows of a torpedo level, as shown and described.

DESCRIPTION

FIG. 1 is a top perspective view of vial windows for a torpedo level, illustrating the vial windows as part of a torpedo level shown in broken lines.

FIG. 2 is a front elevation view of FIG. 1.

FIG. 3 is a rear elevation view of FIG. 1.

FIG. 4 is a top plan view of FIG. 1.

FIG. 5 is a bottom plan view of FIG. 1; and,

FIG. 6 is a right-end elevation view of FIG 1, the left-end view being identical.

The broken lines are provided for illustrative purposes only and form no part of the claimed design.
